US0D1081110S

(12) United States Design Patent (10) Patent No.: US D1,081,110 S
(45) Date of Patent: * Jul. 1, 2025

(54) PILL DISPENSER

- (71) Applicant: Athena Club Holdings, Inc., New York, NY (US)
- (72) Inventors: Charles Desmarais, New York, NY (US); Maria Markina, New York, NY (US); Joshua Morenstein, San Francisco, CA (US); Christopher Nicholas Hibmacronan, Oakland, CA (US); Myung Jae Park, San Francisco, CA (US)
- (73) Assignee: Athena Club Holdings, Inc., New York, NY (US)
- () Term: 15 Years
- (21) Appl. No.: 29/846,113
- (22) Filed: Jul. 13, 2022
- (51) LOC (15) Cl. 03-01
- (52) U.S. Cl. USPC D3/203.2
- (58) Field of Classification Search
USPC D3/203.1, 203.2, 203.3, 203.4, 203.5, D3/203.6, 203.7, 203.8, 201, 205, 264, D3/273, 295, 302, 901-905; D9/420, D9/421, 756, 757, 759, 549, 737, 738
CPC A61J 1/00; A61J 1/03; B65D 83/04; B65D 83/0445; B65D 83/0481; B65D 2583/04

(57) CLAIM

The ornamental design for a pill dispenser, as shown and described.

DESCRIPTION

FIG. 1 is a front perspective view of a pill dispenser; FIG. 2 is a front view of the pill dispenser illustrated in FIG. 1; FIG. 3 is a rear view of the pill dispenser illustrated in FIG. 1; FIG. 4 is a left side view of the pill dispenser illustrated in FIG. 1; FIG. 5 is a right side view of the pill dispenser illustrated in FIG. 1; FIG. 6 is a top view of the pill dispenser illustrated in FIG. 1; and, FIG. 7 is a bottom view of the pill dispenser illustrated in FIG. 1.

The broken lines in the figures show disclaimed portions of the pill dispenser and form no part of the claimed design. The thin solid lines illustrate surface contour and form no part of the claimed design.

1 Claim, 7 Drawing Sheets
